UNITED STATES PATENT OFFICE.

AARON WOLF AND ANTONI GOVERNAL, OF NEW YORK, N. Y., ASSIGNORS TO METALLIC FLEXIBLE HOSE COMPANY, OF BROOKLYN, NEW YORK, A CORPORATION OF NEW JERSEY.

CORNER-POST FASTENER.

1,143,796.

Specification of Letters Patent. Patented June 22, 1915.

Application filed June 11, 1912. Serial No. 703,004.

To all whom it may concern:

Be it known that we, AARON WOLF and ANTONI GOVERNAL, both citizens of the United States, and residents, respectively, 5 of the city of New York, borough of Manhattan, in the county and State of New York, and of the city of New York, borough of Brooklyn, in the county of Kings and State of New York, have invented a 10 new and Improved Corner-Post Fastener, of which the following is a full, clear, and exact description.

This invention relates to certain improvements in corner post fastenings, and more 15 particularly to that type in which the parts serving to connect the side rail to the metal corner post are formed from sheet metal.

In our improved construction, we provide 20 for the direct attachment of the side rail to the corner post connection without necessitating the employment of any connecting member on the side rail. This in the preferred construction is accomplished by attaching a short tubular member to the post 25 with its open end adapted to receive the end of the side rail.

One important feature of our invention relates to the means for supporting and securing this side rail within the tubular 30 member.

Reference is to be had to the accompanying drawings, forming a part of this specification, in which similar characters of reference indicate corresponding parts in all 35 the views, and in which—

Figure 1 is an end view of our improved construction showing the side rail in section; Fig. 2 is a top plan view, the post being shown in section on the line $b-b$ of 40 Fig. 1; Fig. 3 is a vertical section on the line $a-a$ of Fig. 2; Fig. 4 is a perspective view of the tubular member disconnected from the post and the wedge for securing it in place, the side rail being shown in dotted 45 lines; Fig. 5 is a perspective view of the side rail supporting member adapted to be permanently secured within the tubular member; and Fig. 6 is a perspective view of a portion of the angle iron connecting adjacent corner post fastenings. 50

We have illustrated our invention as ap-

plied to a portion of a bedstead having a metal corner post 10 square in cross section. Our invention is equally applicable to corner posts of circular or any other cross sectional form. The side rail is formed of the ordinary angle iron 11 and the two corner posts at each end of the bedstead are connected together by transverse bars or angle irons 12. 55 60

The tubular member 13, which we employ for securing the side rail to the corner post, is formed of a single piece of sheet metal bent to substantially rectangular form, as shown in Fig. 4. The edges of the 65 sheet may be secured together in any suitable manner, but preferably the bottom side 14 of the tubular member projects laterally beyond the inner vertical side 15, and this side has two lugs 16 projecting through 70 openings in the lower side 14 and riveted or swaged over to hold the two sides together. The inner side 15 preferably has a portion cut and bent laterally to form a flange 17, to which the connecting bar 12 between the corner post may be bolted or riveted. For securing the tubular member to the post, we provide two opposite sides of the tubular member, preferably the top side 18 and the bottom side 14, with extensions 80 19 and 20 adapted to extend through horizontal slots in the post, and terminate within the interior of the post. Each extension has an opening therethrough, so that after they have been extended through slots to 85 bring the end of the tubular member flush against the outer side of the post, a wedge 21 may be driven down into these openings to firmly and permanently secure the tubular member to the corner post. 90

The tubular member is of an interior width and height substantially equal to the width and height of the angle iron forming the side rail 11, so that when the rail is projected into the end of the tubular member, 95 it will engage with the top and one side of said tubular member.

To rigidly support the side rail in position, we provide a supporting member adapted to be rigidly and permanently secured within the tubular member, and of such form that it will support the upper 100

horizontal flange of the side rail and hold the side flange against the side wall of the tubular member. This supporting member 5 may assume various different forms, but is preferably constructed as illustrated in Fig. 5. The member has a base 22 adapted to be riveted or otherwise rigidly secured to the bottom wall 14 of the tubular member, and has an end wall 23 and a side wall 24. The 10 side wall extends along the inner surface of the side wall 15 of the tubular member so as to support the free edge of the horizontal flange of the side rail along the length of the latter, and the end wall is of such size 15 that it supports said horizontal flange of the side wall across the entire width of the latter, and, at the same time, holds the vertical flange of the angle iron against the vertical side of the tubular member. It will 20 thus be noted that the tubular member with the supporting member secured therein, presents an end opening of the proper size and shape to receive the side rail, and when the side rail is in position, it is supported along 25 its length at both sides and across its width at the open end of the tubular member.

For securing the side rail in position, suitable locking means is employed, which in the form illustrated, constitutes a wedge 30 25. The top and bottom walls 18 and 14 of the tubular member, the base 22 of the supporting member and the horizontal flange of the side rail, are all perforated, so that when the side rail is in proper position, the wedge 35 25 may be dropped into place and the withdrawal of the side rail positively prevented. The wedge is preferably of such length that when in position, it projects slightly below the lower surface of the tubular member; thus, to remove the wedge, it is merely necessary to strike it a sharp blow on the lower end, and it will be so loosened that it may be readily withdrawn.

It will be noted that the side rail does not 45 have any part of the connection permanently secured thereto and that the entire connection is permanently secured to the corner post. Thus, in the handling or shipping of the bedstead, there are no parts which are liable to become lost and the side rails may 50 be made up of ordinary angle irons and may be cut by any machinist to vary the length of the bed as desired.

In shipping the bed, the head and the foot 55 may be rigidly secured together by short pieces of angle irons held in the tubular members by the wedges, and as these short pieces do not require any special work upon them except the cutting and punching of the slots for the wedges, a considerable saving is 60 effected over the special casting connections commonly employed in the shipping or storing of metal bedsteads.

Various changes may be made in the construction and arrangement of the parts with-

in the scope of the appended claims and without departing from the spirit of our invention.

Having thus described our invention, we claim as new and desire to secure by Letters Patent:

1. A corner post fastening, including a tubular member adapted to be detachably secured to the corner post in a substantially horizontal position, a horizontally-disposed side rail in alinement with said tubular member, a supporting member secured within said tubular member and presenting supporting faces for the lower side and one lateral face of said side rail, and means for detachably securing said side rail in position. 75 80

2. In combination, a corner post, a tubular member rigidly secured to said post, an angle iron projecting into said tubular member and having an upper horizontal flange and a vertical side flange, and a member within 85 said tubular member for supporting said angle iron along the length of the free edge of the horizontal flange.

3. In combination, a corner post, a tubular member secured thereto, an angle iron slideable endwise into the end of said tubular member, and a supporting member secured within said tubular member and presenting supporting edges extending transversely and 90 longitudinally of said angle iron.

4. In combination, a corner post, a tubular member attached to said post and having a portion of one side struck out to form a lug and leaving an opening, a side rail, and a 100 member serving to support said side rail and having a portion within said tubular member covering said opening and a portion serving together with said side rail to close the end of said tubular member. 105

5. In combination a corner post, a tubular member secured thereto and formed from a sheet metal blank, said blank being provided with spaced apertures therethrough adjacent to one edge, and the opposite edge of said blank being provided with separate spaced projections adapted to enter said apertures along the length of said tubular member, said tubular member having a portion of one side wall thereof between said projections bent outwardly to form a lug, extending in a vertical plane at right angles to the plane of said side wall, a side rail detachably connected to said tubular member and a cross rail connected to said lug. 110 115 120

6. A corner post fastener including a member formed from a sheet metal blank and adapted to be secured to a corner post, said member having an opening in the end thereof opposite to said post and into which a side rail may slide endwise, a supporting member within said first mentioned member and presenting a transversely extending edge for engagement with the under side of said side rail, and a fastening member extending 125 130

vertically through said first mentioned member.

7. In combination, a corner post, a member formed from a sheet metal blank and 5 detachably secured thereto, said member having parallel, vertical, spaced walls, a side rail having the end portion thereof slidable endwise into said member between said walls, a supporting member within said first 10 mentioned member for engagement with the lower side of the end portion of said side

rail, and a removable fastening member extending vertically through said first mentioned member between said walls.

In testimony whereof we have signed our 15 names to this specification in the presence of two subscribing witnesses.

AARON WOLF.

ANTONI GOVERNALE.
